UNITED STATES PATENT OFFICE.

ASA B. FISK, OF LYNDONVILLE, NEW YORK.

FRUIT-PACKAGE.

SPECIFICATION forming part of Letters Patent No. 258,906, dated June 6, 1882.

Application filed February 9, 1882. (Model.)

To all whom it may concern:

Be it known that I, ASA B. FISK, a citizen of the United States, residing at Lyndonville, in the county of Orleans and State of New York, have made certain Improvements in Fruit Packages, of which the following is a specification.

This invention relates more particularly to a species of connecting cover for peach-baskets, which can be fastened on to prevent damage to the fruit and theft and allow the baskets to be packed in rows on top of each other for storage or shipment, and the covers returned to the shipper, irrespective of the baskets, for future use; and the invention consists in the construction and arrangement of said cover, which is intended for two baskets together. It also consists in an improved fastening device, all as hereinafter fully explained.

In the drawings, Figure 1 is a side elevation, showing the cover fastened to two baskets; Fig. 2, a detail in perspective of one end, showing the fastening; and Fig. 3, details of the fastening.

A represent two slats or side pieces, with the two ends B B fastened thereto. These side slats are fastened a little below the top of the end pieces, so as to leave a long space, a, and wide enough for the shoulder or rim b of a peach-basket to rest on the edge of slats A, as shown in Fig. 1.

The top D is made of slats also, with spaces between, to secure ventilation, and comes down on the top of the baskets C C and rests on the upper edges also of ends B B, and thus holds the shoulders b b of the baskets against the top edge of the slats A A, preventing the baskets from dropping out, thus making an effectual cover to the baskets. This top D is held on the side and end frame, A B, by a bent hasp, c, of wire, the upper part setting in a groove in a piece of wood, D', fastened to the cover to strengthen it. The hasp swings up and down in this. It is bent down sharply at the edge of the cover, as shown, and set over an eccentric piece of iron, g, pivoted above its center to the end of the box B, as shown in

Figs. 2 and 3. The under side of this piece g is recessed out, as shown at f, and under this lip g' the hasp sets, as fully shown in Fig. 1. 50

To unfasten or fasten the hasp the locking-piece g is swung round on its pivot so that the lip g' is uppermost. If to be fastened, the lip part is swung down, and, being pivoted eccentrically, the heavier or lower part remains 55 down over the end of the hasp until unfastened by hand.

This locking device may be at both ends, if desired; but usually one end will have a hasp over a fixed lip or button, which acts as a kind 60 of hinge at that end.

This cover is of great importance to peach-shippers, as baskets have now to be covered with cloth or thin muslin to protect the fruit from theft, &c.; but no such baskets can be 65 set on top of each other in store or cars. The expense of the cloth for a large shipment is great, as it is an entire loss.

My cover will allow any number of tiers set on top of each other. It locks up the baskets 70 and protects the fruit entirely.

I claim—

1. In combination with a peach basket or baskets, C C, having a rim or shoulder, b, around the upper edge, the cover and frame consisting of the slats A A, ends B B, and top D, arranged so as to leave the space a at the sides, between the top D and sides A A, and suitable fastening devices, substantially as and for the purpose specified. 75

2. In combination with the basket C and covering A B D, the locking device consisting of the bent hasps c c, stay-piece D', and eccentrically-pivoted locking-piece g g', all arranged and operating substantially in the manner and 85 for the purpose specified.

In witness whereof I have hereunto signed my name in the presence of two subscribing witnesses.

A. B. FISK.
